CONTINUOUS AUTOMATIC CONCRETE MIXER

Filed Aug. 4, 1926

UNITED STATES PATENT OFFICE.

MILTON F. HORST, OF LOS ANGELES, CALIFORNIA.

CONTINUOUS AUTOMATIC CONCRETE MIXER.

Application filed August 4, 1926. Serial No. 127,009.

My invention relates to an apparatus for thoroughly and effectively mixing concrete, which apparatus may be of the stationary type, but preferably portable, and positioned on a truck of any desired form, either operated by its own power or by any draft appliance, actuated either by animals or motor, and more particularly comprises an improvement on the construction disclosed 10 in my prior Patent #1,516,293, granted to me November 18, 1924, for a continuous automatic concrete mixer.

It accordingly is an object of my invention to provide a novel form of concrete mixer, preferably of portable form, in which sets of appliances are provided for automatically lifting the concrete materials; giving them a preliminary mixing, then thoroughly and effectively agitating said materials in a novel form of mixing chamber by means of sets of stationary and movable mixing elements, which elements insure a thorough mixing of said materials in a dry state, and an additional mixing while in a wet state, the resulting wet mixture being conveyed to any elevated or distant point found in practice desirable.

It is also within the province of my invention to provide a means in the form of a clutch whereby one of the lifting means, for example that used for elevating the gravel, may, when desired, be placed out of commission so that a surface concrete comprising sand and cement only may be prepared.

A further object of my invention is to provide a novel form of mixing or agitating element, which may take the shape of a pivoted reversely positioned, shallow curved plate or set of such plates, each plate being equipped with a hinged portion, spring-controlled, to coact with a set of stationary elements, also of warped, shallow and curved construction, to the end that the concrete materials are thoroughly agitated and mixed, and that under no circumstances will said elements be subject to injury in case an obstruction, such as a rock or pebble, should become lodged between said elements, or between said elements and the walls of the mixing chamber.

Another object of my invention is to provide a novel means for extending the auto-

matic mixed discharge means whereby the mixed concrete may be lifted story by story 55 to the top of a building, or to any desired point of discharge.

It is moreover within the province of my invention to provide a special means for operating the movable mixing elements, which 60 may take the form of a motor operated master gear which is in mesh with pinions associated with said elements whereby they may be operated in unison.

It is also an object of my invention to provide a novel structure whereby the concrete discharge means, preferably in the form of automatically operated conveyers, may be swung in any preferred arc, and positioned or anchored at any convenient 70 point on a building or other place, the mixed concrete being thus elevated to the point of use or any other distant point desired.

It is also an object of my invention to provide a novel form of concrete mixer which 75 is simple in character, composed of a minimum number of parts, not easy to get out of order, thoroughly reliable and efficient in operation, and one which will thoroughly and reliably effect the objects intended.

Further objects and advantages of my invention will become more apparent as the description thereof proceeds.

Reference is had to the accompanying drawings, in which similar reference characters denote similar parts. In the drawings,

Fig. 1 is a broken side elevation of the preferred form of my apparatus,

Fig. 2 is a top plan view of Fig. 1. 90

Fig. 3 is an enlarged cross-sectional view of Fig. 1, taken on the line 3—3, and looking in the direction of the arrows.

Fig. 4 is a fragmentary detail sectional view taken on the line 4—4. Fig. 2, also 95 looking in the direction of the arrows,

Fig. 5 is an enlarged detail section on the line 5—5, Fig. 2, looking in the direction of the arrows.

Fig. 6 is a top plan view of the mixing 100 chamber, on a somewhat smaller scale than Fig. 1, with the cover removed,

Fig. 7 is an enlarged fragmentary cross-sectional detail view taken on the line 7—7, 105 Fig. 6, looking in the direction of the arrows,

Fig. 8 is a similar view on the line 8—8, Fig. 2,

Fig. 9 is an elevational view of the mechanism for transmitting the movement of one of the concrete discharging conveyers to the other so that both may be swung about on an arc or in anyway desired, especially when it is desired to add units to provide for increased elevation,

10 Fig. 10 is an enlarged detail view of a suggestive form of clutch that may be used for putting out of commission one of the lifting conveyers, and

15 Fig. 11 is a section on line 11—11, Fig. 9. Describing my invention more in detail, the purpose of my invention is to provide an apparatus for receiving the concrete materials, such as sand, cement, and gravel, lift each individually into a chamber where 20 they are given a preliminary mixing, and then thoroughly agitate and mix said materials in a dry state, and finally mixing them wet, after which the mixed concrete in a wet state is conveyed to any point of 25 discharge, so that when it is discharged there will be insured that the various materials or ingredients are thoroughly commingled.

As seen in Figs. 1 and 2, my improved 20 apparatus is preferably made portable and mounted on a truck 2, drawn either by its own motor mounted thereon, or drawn by draft in any manner in practice found desirable. On the truck 2 is mounted in any 25 preferred manner and of any desired construction, a frame work 4 consisting of suitable plates, bars, braces and the like, riveted or bolted or thoroughly secured together with additional plates, or without, or with angle irons, or in any manner found in practice 30 desirable, and secured to the frame work 4 is a casing 6 of suitable construction, but preferably annular in form, and braced and supported in position as desired.

The casing 6 has an outer preferably 45 circular wall 8 and an inner similarly shaped wall 10 spaced therefrom and fixed to the frame work 4 as above indicated, and also may be provided with a cover or closure 50 12. As seen more particularly in Fig. 7, between the walls 8 and 10 of the casing 6 a rotatable bottom 14 is positioned, said bottom being adapted to be rotated between said walls for the purpose of conveying the mixed concrete material to the outlet hereinafter more fully described. Said bottom 55 is rotated by means of any desired number of braces or operating elements 16 associated in any preferred manner with said bottom and a rotatable vertically positioned shaft 18 presently to be more particularly identified.

Positioned within the mixing chamber or 60 casing 6 at suitably spaced points is a series of stationary mixing elements 20, which 65 elements are secured to the walls 8 and 10

in any manner in practice found desirable, and depending within said casing is a circular series of rotatable agitating or mixing elements 22, each preferably positioned between the stationary elements 20, and in close proximity with the rotating bottom 14, which bottom, if desired, or the casing itself, may be suitably packed to prevent leakage.

Each stationary mixing element 20 is of 75 warped, shallow curved form so as to facilitate agitating and mixing of the concrete materials, and also to prevent the lodging of any of the coarser ingredients of said materials, such as pebbles or rocks, or even 80 prevent the cement from adhering to the walls of the casing, as is done with known constructions, necessitating its removal, frequently by the use of a chisel, as is well known.

85 To prevent injury to both the stationary and movable mixing elements, the latter are of special construction. To facilitate proper and efficient mixing, each element 22 is 90 associated with the pivot 24, being securely fastened thereto in any preferred manner, 95 said elements being rotated by a set of vertical stub shafts 26, depending within the casing 6 and through openings in the top of cover 12, or otherwise, as presently to be described. Said elements 22, see more particularly Fig. 7, have any preferred number of reversely positioned, warped, shallow blades 26 extending from the pivot 24, and each blade is equipped with a hinge 28, a flat or other shaped spring 30 being provided to permit said blades to swing in case any obstruction, as above referred to, is encountered, thus effectively preventing said blades from injury. Suitable spokes or 100 braces 32 (Fig. 6) are provided to brace the casing or mixing chamber 6 to prevent its collapse.

105 Secured to each stub shaft 26 is a pinion or gear 34 by means of a key or otherwise, 110 and each gear is in mesh with a master gear wheel 36, equipped with spokes or other members 38, said master gear being keyed at 40, or otherwise secured to the vertical shaft 18 and of course rotating therewith, 115 the pinions 34 all rotating in unison as the master gear 36 is rotated by said shaft.

120 Attention is now directed to Figs. 1, 2, 3, and 6. As seen more particularly in Figs. 3 and 6, the vertical shaft 18 has secured thereto in any desired manner a gear or pinion 42, in mesh with a worm gear 44 associated in any preferred manner with a horizontal drive shaft 46 positioned in suitable bearings 48, which bearings are mounted as desired on the frame work of the truck 2, said shaft 46 being adapted to be driven through a conventional or other form of reduction gearing 50, suitably housed as indicated in Figs. 1 and 3, by means of the 125 130

motor shaft 52 associated with the motor 3, which, as hereinbefore stated, may also be used to drive the truck, said truck being equipped with ordinary wheels or those of the caterpillar type. As indicated in Figs. 1 and 3, a clutch 54 operated by a hand lever 56, may be used to put into and out of commission the shaft 52 associated with the motor, to actuate the vertical shaft 18 or to stop the same from rotating, and consequently the entire mechanism.

Positioned above the frame work 4, and associated therewith in any manner preferred, is a superstructure 58, which structure is used to support the various conveyers used in lifting the materials or discharging the mixed concrete. As seen in Figs. 1 and 2, a set of conveyers 60, 62 and 64 is used to lift the concrete materials, said conveyers varying in size as shown, depending upon the kind of material to be lifted, and the percentage of ingredients to be mixed. Each of said conveyers depends within a hopper, which hoppers are indicated at 66, 68 and 70, and if desired said hoppers may be equipped with sieves 72 for sifting the materials.

As seen in Fig. 4, each sieve is equipped with a preferably hinged operating means 74, forked at 76, so that said sieve may be placed out of commission as desired, which fork is positioned over a crank 78 actuated by the shaft 80 of the sprocket wheel over which the bucket carrying conveyers are positioned. Of course, this construction is merely suggestive and may in practice be changed to suit working conditions.

Mounted in each hopper is a horizontal shaft 82, associated with said hopper in any manner preferred, and a sprocket wheel of conventional or other type is mounted on each of said shafts, over which the lifting means or elevators 60, 62, and 64 for lifting the concrete materials are positioned, which elevators may be of any preferred endless chain bucket type. Said elevators are securely fastened to the superstructure 4 by any preferred means, as shown more particularly in Fig. 1, the exact structure for accomplishing this being immaterial. Said elevators are operated in unison by a means associated with the vertical shaft 18, and of course are operated in timed relation therewith.

As just stated, each end of each of the conveyers or elevators is equipped with a sprocket wheel over which the endless chain rides, and the upper sprocket wheels are mounted upon a flexible shaft 84, made so by the use of any preferred form of universal joint, any preferred number being used. This feature permits the conveyers to be positioned as shown, or in any other, if preferred.

When it is desired to provide surface con-

crete, only sand and concrete are mixed in proper relations. To provide for this feature, I equip my apparatus with a means for putting temporarily out of commission the conveyer or elevator lifting the gravel, and to this end I provide the flexible shaft 84 with any desired form of clutch 86, which may be of conventional or other form.

Any means for operating the conveyers 60, 62 and 64 may be provided, but I preferably equip the flexible shaft 84, at any convenient point, with a sprocket wheel 88, a similar sprocket wheel 90 being positioned on a short shaft 92. Mounted in bearing 94 on the superstructure 4, said sprocket wheels being connected by an endless chain 96. On the vertical shaft 18 is mounted a horizontal bevel gear 98, in mesh with a vertical bevel gear 100 mounted on the short shaft 92, said vertical shaft 18 accordingly operating the elevators in timed relation. It will be understood of course, that this construction is suggestive merely, and may in practice be changed as desired.

As the elevators 60, 62 and 64 lift the concrete materials, they are given a preliminary mixing, and for this purpose a hopper or chamber 102, shown more particularly in Fig. 5, is provided, which hopper may be secured to the superstructure 4 in any manner preferred, the exact construction being immaterial. If desired, a cut off valve 104 may be positioned in the bottom of the hopper 102 to regulate the quantity of materials fed to the mixing chamber 6.

As seen more particularly in Figs. 2 and 6, the mixing chamber 6 is equipped with a discharge opening 106, positioned in an offset portion 110, either integral with the outer wall 8 thereof or associated therewith in any manner desired, a preferably straight mixed concrete deflecting wall 108 extending across said chamber to insure that said concrete will be deflected into the hole 106 and all possibility of any of the material piling up being thus eliminated. The hole 106 leads to another hopper 112, see Fig. 1, which hopper has associated therewith a discharge conduit 114, discharging the mixed concrete into the buckets of an elevator or conveyer 116, similar to those previously described but constructed in such a manner that it may be lengthened by adding units thereto so that, if desired, the mixed concrete may be lifted to the top of a building, a larger bucket carrying endless chain, of course, being provided.

As seen more particularly in Fig. 1, the elevator 116 is inclined but a small angle from the vertical or perpendicular to the base of the apparatus, and this feature permits the extension units to be added, without moving the apparatus. The elevator 116 is operated from the shaft 46, see Fig. 3, by means of the bevel gears 118 and 120, the

latter being positioned on a short shaft 122 mounted in suitable bearings on the framework 2, a lower sprocket wheel being provided on the shaft 122, over which the endless chain of the elevator is positioned.

The means whereby additional units may be supplied to the elevator 116 is shown more particularly in Fig. 8 and comprises a cutaway projection 124 bolted or otherwise detachably associated with the sprocket wheel 126 to receive the same, said portions being of any preferred shape, and bolted to the superstructure 4, the socket supporting the upper sprocket of the elevator, as shown in Fig. 8. When it is desired to increase the length of said conveyer or elevator, the socket 126 is unbolted from the projection 124 and as many units added to obtain the proper length so that the mixed concrete may be lifted to the top of the building if desired, a longer endless chain with buckets being of course provided. The additional units may be detachably secured to the building by bolts or any preferred type of hangers, either of conventional or other form as desired.

The elevator 116 may of course discharge the mixed concrete directly to the point desired, but if it is preferred to carry said concrete to some distant point, an additional discharge conveyer 128, of the same type as those previously described, may be provided, the elevator 116 discharging its contents into a chute 130, secured to the superstructure 4, which chute has a hole or pipe 132 for discharging the mixed concrete onto the conveyer 128, the extreme end of which is preferably supported upon a pair of standards or props 134, placed wherever needed to support the outer end of said conveyer. If desired, a hopper or chute 136, with a jointed pipe 138, may be associated in any desired manner with the conveyer 128, or may be anchored onto the props or standards 134 as shown, the pipe 138 being used to discharge the concrete into the wall of the building or into any other desired place.

To provide for swinging the conveyer 128 in any arc or position desired, and at the same time to operate the same in timed relation with the conveyer 116, a special construction must be provided. See Fig. 9. To this end the conveyer 116 has its upper sprocket wheel equipped with a bevel gear 140 in mesh with a similar gear 142 secured to the flexible extensible shaft 144, equipped with the universal joints 146 of any preferred type, the shaft 144 being mounted in suitable bearings, as shown, in the superstructure 4, the exact construction being immaterial and hence not described, in detail, bevel gears 147 and 148 being in mesh so that the conveyer 128 may be driven in timed relation with the conveyer 116.

As will be clear, when additional units are provided to lift the concrete to different heights, the conveyer 128, together with the gears, shaft 144 and socket 126 are lifted bodily and swung about as needed, and anchored by means of suitable hangers or the like to any part of the building under construction or to the scaffolding associated therewith, so that the mixed concrete may be readily discharged at the desired points, and that without moving the apparatus. 70 75

As will now be clear, the concrete materials are thoroughly agitated and mixed dry for a portion of the rotative stroke of the rotatable bottom 14 of the mixing chamber 6. For the remainder of said stroke said materials are mixed wet. To this end a water pump 150 equipped with a suction pipe 152 is positioned on the truck at any convenient point, and is operated by the chain or other drive 154 from the shaft 46. A discharge pipe 156, leading to a perforated or other connection 158 for spraying the water into the mixing chamber 6 is provided. Any other means for wetting the mixture may of course be provided. 80 85 90

The operation of my apparatus should now be clear. The truck being placed in proper position, the hoppers 66, 68 and 70 are lowered in position, and the conveyer 95 propped or secured in the place desired.

The concrete materials are then dumped into said hopper and power applied to the apparatus by using the hand lever 56 to throw in the clutch 54, setting the worm gear 44 in motion, said gear through the pinion 42 rotating the vertical shaft 18. 100

The shaft 18 rotates the bottom 14 through the braces or operating members 16. At the same time said shaft rotates the master gear wheel 36, rotating in unison the pinions 34 to rotate the mixing or agitating elements 22. Said worm gear also rotates the shaft 46 which in turn actuates the bevel gears 118 and 120 to rotate the shaft 122 110 to actuate the discharge conveyer 128; and the pump 150 is operated by the chain 154.

As the shaft 18 is rotated, the gears 98 and 100 are actuated, thus operating the chain 96 to rotate the shaft 84 which operates the lifting means or elevators 60, 62 and 64, the concrete materials being deposited into the preliminary mixing chamber and hopper 102. The discharge elevator 116 actuates the conveyer 128 through the gearing 120 and shaft 144. 115

The valve 104 being opened, the materials are dropped into the mixing chamber 6, where they are carried by the bottom 14 and are thoroughly agitated and mixed dry 125 by the mixers 20 and 22, until the perforated pipe 158 is reached, after which they are again agitated and mixed in a wet state, insuring that a perfect concrete mixture is formed. 130

The wet mixed concrete, by reason of the straight wall or partition 108, is discharged through the chute 106, pipe 114 and into the buckets of the discharge elevator 116, said elevator discharging the concrete into the hopper 130, chute 132 and onto the conveyer 134, after which it is discharged through the pipe 138 to the point desired.

While I have thus described my invention with great particularity, it will be clear that the same may be modified throughout a wide range. I accordingly do not propose to be limited to the exact details of construction shown and described, but reserve the right in practice to make any and all modifications thereof that fall within the scope of the appended claims.

I claim as my invention:

1. A continuous automatic concrete mixer comprising in combination, a set of hoppers for receiving the materials to be mixed, an annular casing, a mixing chamber associated with said casing, a set of conveyers for elevating said materials into said mixing chamber, stationary and rotary mixing elements in said casing, said rotary elements being positioned between said stationary elements, means associated with said casing whereby the mixed concrete may be moved dry for a portion of the circumference of a circle, means associated with said casing whereby said mixture may be moved wet for the remaining portion of said circumference, a set of conveyers for receiving and elevating the wet mixed concrete to the point of discharge, and means associated with said mixer for operating the movable parts in timed relation.

2. In a portable automatic concrete mixer, in combination, a framework, a casing mounted on said framework, a circular movable element associated with said casing, stationary and movable mixing elements associated with said casing, said rotary elements being positioned between said stationary elements, means associated with said casing and said framework, whereby the concrete materials may be given a preliminary mixture, means for mixing said materials both dry and wet, and means associated with said framework for operating the movable parts of said mixer in timed relation.

3. In an automatic concrete mixer, in combination, automatic means for giving the concrete materials a preliminary dry mixture, means associated with said first means for rotating said dry mixture, stationary and movable means for mixing said dry mixture as it is rotated, said movable means being positioned between said stationary means, means for mixing said dry mixture with water as it is rotated, and means for moving each of said means in timed relation.

4. In an automatic concrete mixer, in combination, a stationary annular casing, a mov-

able bottom, for said casing for moving the concrete mixture, stationary and rotatable mixing elements in said casing, said rotatable elements being positioned between said stationary elements, a pinion associated with each of said rotatable elements, a master gear for rotating each of said pinions, means for wetting said mixture, and means for moving said moving parts in timed relation.

5. An automatic concrete mixer comprising in combination an annular stationary casing comprising inner and outer concentrically positioned walls, a moving bottom between said walls, a receptacle for receiving material to deposit the same on said bottom, and sets of stationary and movable mixing elements being alternately positioned so that they are adapted to coact for thoroughly mixing said material.

6. A concrete mixer comprising in combination a fixed annular casing equipped with a movable bottom, automatic means for delivering sand, cement and gravel or sand and cement alone to said bottom, and alternately positioned sets of circular stationary and moving mixing elements associated with said casing, and automatic means for moving said moving elements.

7. In a concrete mixer, in combination, a stationary annular casing having concentric walls, a travelling bottom between said walls, automatic means for depositing concrete materials on said bottom alternately positioned sets of stationary and movable mixing elements associated with said casing for acting on said materials, and automatic means for discharging the mixed material through the outer wall of said casing.

8. A concrete mixer comprising a stationary annular casing, an annular bottom plate movable in said casing, a cover for said casing, means for delivering concrete material into said casing, a circular series of alternately positioned stationary and movable mixers in said casing for mixing said materials, rotary means positioned above and associated with said movable mixers for operating them in time relation, means associated with said casing whereby the mixed material may be discharged therefrom, and means positioned centrally of said casing whereby the moving parts may be moved in timed relation.

9. An apparatus of the class described comprising an annular mixing chamber, closures for the top and bottom of said chamber, means whereby material may be deposited in said chamber, mixed, and discharged therefrom, a plurality of alternately positioned stationary and rotary mixers for accomplishing said mixing, and means for delivering water into said material at a point remote from the deposit of said material in said chamber.

10. In an apparatus of the class described,

in combination, a stationary annular mixing chamber, means for closing the bottom and top of said chamber, a hopper associated with said top, means for depositing material into said hopper and thence to said chamber, means associated with said casing for moving the material deposited therein in a circular path, alternately positioned stationary and moving means for agitating 5 said material at all points as it is moved, means for discharging the mixed material from said chamber, and means for elevating the mixed material to a distant form of discharge, said last means being inclined 10 at a comparatively small angle from the perpendicular to said chamber.

11. In a concrete mixer, in combination, a mixing chamber, automatic means for depositing concrete materials in said chamber, alternately positioned stationary and movable mixing means in said casing for thoroughly mixing said materials in a dry state and then in a wet state, sets of elevating and discharging means whereby, 15 the mixed materials may be discharged to any point desired, a motor, a pump operated by said motor, means associated with said pump for discharging water into said chamber, a gear reduction unit associated with 20 said motor and said pump, and means associated with said motor for operating the moving parts of said mixer in timed relation.

12. In a concrete mixer, in combination, 35 a mixing chamber, a set of hoppers for receiving severally the concrete materials, elevating means for each of said hoppers for elevating said materials and depositing them into said chamber, means associated 40 with one of said elevating means whereby it may be temporarily placed out of commission, means associated with each of said hoppers whereby one or more of said hoppers may be placed out of commission, and 45 a set of detachable appliances for elevating the mixed material to any point desired, so that additional appliances may be added thereto for said purpose.

13. A mixing chamber adapted for special 50 use in connection with a concrete mixer, said chamber comprising an annular casing, top and bottom closures for said casing, and a alternately positioned set of stationary and movable mixing elements in said casing, said 55 mixing elements comprising single shallow curved blades, and reversely positioned shallow curved blades.

14. In a concrete mixing apparatus, a mixing chamber, a set of rotatable mixing elements positioned in said chamber, and a mechanical movement for said elements, said movement comprising an annular gear, and a set of pinions associated with each of 60 said elements and adapted to be operated 65 by said gear.

15. In an apparatus of the class described, in combination, a mixing chamber, means for depositing materials to be mixed into said chamber, means for thoroughly mixing said materials in said chamber, means 70 for adding water to the mixture and again mixing the wet mixture, means for discharging the wet mixture from said mixing chamber, and detachable and attachable means, positioned at such an angle with reference 75 to the apparatus that additional units may be added whereby said wet mixture may be elevated to any point desired.

16. In a conveyor adapted for special use in connection with a concrete mixing apparatus, a lower sprocket adapted to be journaled on said apparatus, an upper sprocket also adapted to be positioned over said sprockets and be moved thereby, and means associated with said upper sprocket, 80 whereby it may be detached and raised, and a conveyer belt of greater length substituted 85 so as to extend the height of the material to be lifted.

17. A sieve mechanism adapted for special 90 use in connection with a concrete mixing apparatus comprising in combination a hopper, a sieve slidable over said hopper, a pitman pivoted to said sieve, and fork means associated with said pitman and a moving 95 part of said apparatus whereby said sieve may optionally be used or not.

18. In a concrete mixing apparatus, in combination, a truck, a mixing chamber on 100 said truck, sets of appliances for automatically depositing cement material into said chamber, appliances associated with said chamber for mixing said material both wet and dry, means for supplying water to said mixing chamber, sets of appliances for 105 conveying the wet mixture to any desired point, means for operating said appliances in timed relation, and means associated with certain of said appliances for optionally placing them into commission or out of commission.

19. In a concrete mixing apparatus, in combination, a mixing chamber, a set of conveyors for depositing concrete materials into 115 said chamber, a set of alternately positioned stationary and rotatable appliances for agitating and mixing said materials, a set of conveyers for discharging said mixture to a distant point, and means associated with said last conveyers for lengthening or 120 shortening the same so that the position of the discharge point may be varied.

20. A mixing chamber for a concrete mixer comprising a rigidly mounted annular casing equipped with inlet and discharge openings, a movable bottom in said casing adapted to carry concrete material from its said outlet opening to said discharge opening, a set of rotatable mixing elements depending 125 into said chamber, and a set of stationary 130

mixing elements positioned between said rotatable elements whereby a thorough mixture of said material is assured.

21. A mixing chamber for a concrete mixer comprising in combination an annular casing, a bottom for said casing adapted to be rotated between the walls thereof, a circular series of alternately positioned concrete mixing and agitating elements depending into said casing and adapted to be rotated in close proximity with the rotating bottom thereof, and a circular series of stationary mixing elements associated with each wall of said chamber and juxtaposed to said 15 rotating elements.

22. A concrete mixer having a set of appliances for selectively lifting concrete material into a mixing chamber equipped with sets of alternately positioned stationary and 20 movable mixing elements whereby said materials are thoroughly agitated and mixed both wet and dry, means for conveying said materials in the circumference of a circle from the point of entry to the point of discharge, 25 and sets of extensible means for lifting the concrete to any point desired.

23. A portable concrete mixing apparatus comprising in combination a truck, a frame work mounted on said truck, a concrete mixing chamber associated with said frame work, a super structure mounted on said frame work, a vertical rotatable shaft extending through said chamber and mounted on said frame work, a rotatable bottom for 30 said chamber, means connecting said bottom and said shaft whereby the latter is adapted to rotate said bottom, a set of rotary mixing devices in said chamber, a pinion associated with each of said devices, an annular internal gear in mesh with each of said pinions adapted to be rotated by said shaft, and sets 35 of appliances for lifting concrete material into said chamber and for discharging the mixed concrete to any convenient point.

45. 24. A concrete mixer equipped with a mixing chamber in which concrete materials are adapted to be mixed, means for lifting said materials into said mixing chamber, means for mixing said materials in said chamber, 50 an extensible mixed concrete lifter discharge means positioned at a small angle with relation to the perpendicular of said mixer, a second discharge lifting and carrying means adapted to receive the mixed concrete from 55 said last named means, means associated with both of said last mentioned means for operating the same in timed relation, said last means having a set of universal joints associated therewith so that both of said 60 discharge means may be swung about in any desired manner.

25. A concrete mixing apparatus equipped with means for mixing concrete, a set of conveyers for carrying away the mixed con-

crete, a set of bevel gears for operating said 65 conveyers in timed relation, a shaft for connecting certain of said gears, and a set of universal joints associated with said shaft whereby said gears will be made to function irrespective of the manner in which 70 said conveyers are shifted.

26. In a concrete apparatus, in combination, a set of hoppers for receiving the concrete materials, a frame work, a superstructure associated with said frame work, a mixing chamber securely mounted on said frame work, a set of conveyers associated with said hoppers and said superstructure for lifting said materials into said chamber, an upper shaft associated with said conveyers for 80 operating them in unison, a set of universal joints associated with said upper shaft, a lower shaft for each of said conveyers and mounted in each of said hoppers, and means associated with said mixing chamber for 85 conveying away the mixed concrete to any point desired.

27. In a concrete mixing apparatus, in combination, a framework, a super structure mounted in said frame work, a mixing chamber associated with said frame work, a vertical shaft mounted centrally of said chamber, concrete material lifting means associated with said super structure for lifting said material into said chamber, means associated with said shaft and said lifting means whereby said shaft functions to operate said lifting means, a set of mixing devices depending from said super structure and positioned within said chamber, a pinion for 90 each of said devices, a master gear wheel hinged to said vertical shaft and in mesh with each of said pinions, means associated with the lower portion of said shaft for rotating said shaft, a set of power actuating 95 appliances for operating said last means and means associated with said mixing chamber for conveying the mixed concrete to a distant point.

28. In a portable concrete mixing apparatus, in combination, automatic motor operated means for lifting and mixing concrete materials, a set of mixed concrete discharge conveyers for conveying said concrete to any point desired, means associated with 100 each of said conveyers whereby one of said conveyers may be extended and anchored to a building or other point, and means associated with both of said conveyers whereby 105 both may be swung about in any desired direction to provide for said anchoring and so that said mixed concrete may be elevated and discharged at any desired elevated point or at any desired distance.

In testimony whereof I have signed my 110 name to this specification.

MILTON F. HORST.
